UNITED STATES PATENT OFFICE.

LACEY Y. WILLIAMS, OF TOLEDO, OHIO.

DUST-GUARD.

1,116,963.

Specification of Letters Patent.

Patented Nov. 10, 1914.

Application filed April 29, 1912. Serial No. 693,822.

To all whom it may concern:

Be it known that I, LACEY Y. WILLIAMS, a citizen of the United States, residing at Toledo, in the county of Lucas and State of Ohio, have invented certain new and useful 5 Improvements in Dust-Guards, of which the following is a specification.

The object of the invention is the provision of a guard especially adapted for insertion within the chamber at the rear end 10 of a car journal box and which shall frictionally engage one of the vertical surfaces, preferably the front surface, bounding the chamber under all conditions of service, and 15 thus prevent dust and dirt or other foreign substance or substances passing to the interior of the box and to the journal bearing.

The invention consists in a dust guard having at one of its vertical surfaces, and 20 preferably both at the top and bottom thereof, spring means for forcing the opposite vertical surface against the vertical surface bounding the box chamber.

Finally, it consists in certain novelties of 25 construction and combinations of parts as hereinafter set forth and claimed.

The accompanying drawing illustrates an example of the physical embodiment of the 30 invention constructed according to the best mode of procedure I have so far devised for the purpose.

Figure 1 is a vertical section of a journal box with a guard within the chamber thereof, said guard having at one of its surfaces 35 means for forcing the opposite surface into frictional contact with one of the vertical surfaces bounding the chamber. Fig. 2 is an enlarged plan view of the guard removed from the box chamber, part of one of the 40 retaining plates being removed at the bottom thereof to show the relative locations of certain parts. Fig. 3 is a section on line $\alpha-\alpha$ of Fig. 2.

The particular guard illustrated is comprised of two complementary L-shaped sections A A having edges with curved surfaces B B which, when the sections are assembled, constitute a circular opening for the reception of the journal. The top and 45 bottom edges of the guard are recessed at C C by removing or cutting away part of the material of the sections, and two semi-circular seats D D and one central rectangular seat E may be provided for springs and 50 a roller.

The letter F designates the springs which

are conical coiled springs in this instance, each having an eye G, and H is the roller of any suitable material having a central opening within which is located a small rod or 60 bar I, the ends of which rod or bar are secured within the eyes G of the springs, as shown. To hold the springs and roller in their proper relative positions within a recess C two plates are secured to the guard. 65 The back plate J has an opening K through which the roller projects and a flange L overlapping the end of the guard. The front plate M serves as a bearing for the springs. These plates are fastened to the 70 guard in any way desired, as by brads N, screws or otherwise. The journal box O has a chamber P with front and rear vertical surfaces R and S, respectively.

When the guard is inserted in the chamber the spring pressed rollers at the top and bottom of the guard projecting through the openings K in the back plates will bear against the surface S bounding the chamber, and the springs will force the opposite or 75 plain surface of the guard into frictional contact with the vertical surface R of the chamber and thus prevent the passage of any dust or dirt to the interior of the box. The rollers facilitate the insertion of the 80 guard into the chamber and also allow the separation of the two L-shaped sections and 85 their readjustment when the journal is inserted into the box.

I have illustrated the invention embodied 90 in connection with a dust guard having two L-shaped sections, but it may be embodied in connection with any of the other known forms of dust guards for performing the requisite functions of holding one surface of 95 the guard in frictional contact with one of the vertical surfaces bounding the chamber and excluding foreign substances from the interior of the journal box.

What I claim is:

1. The combination in a dust guard, of 100 sections, each section having an edge with a curved surface, which edges, when the sections are united, form a circular opening adapted to engage a journal, also each section having at another edge a closed recess with an opening thereto, bearing elements 105 each partly located in a recess and partly projecting through the opening to said recess, and a spring within each inclosed recess pressing the bearing element outwardly; 110 the said recesses for the springs and bear-

ing elements being located at opposite sides of the circular opening through the guard.

2. A dust guard having an opening for a journal, and means consisting of rollers and springs, one roller being located each side of the opening, for forcing the guard lengthwise of the journal and against one of the vertical surfaces bounding the chamber of the journal box.
- 10 3. A dust guard having an opening and recesses at opposite sides of said opening, and a roller within each recess with its edge projecting beyond the surface of the guard, for the purpose set forth.
- 15 4. A dust guard having an opening and recesses at opposite sides of said opening, plates each with an opening therein secured to the guard, a roller within each re-

cess and projecting through the opening in a plate, and springs for projecting the 20 rollers.

5. A dust guard having an opening and recesses at opposite sides of the opening, plates with openings inclosing the recesses, a roller in each recess and projecting through 25 an opening in a plate, a rod or bar passed through an opening in each roller, and springs within each recess connected to the rod or bar passed through the roller.

In testimony whereof I affix my signature 30 in presence of two witnesses.

LACEY Y. WILLIAMS.
